Charles F. Cruze and Rollin H. Killoran, Los Angeles, Calif., assignors to Robert H. Clark, Los Angeles, Calif.

Application May 27, 1946, Serial No. 130,129

Term of patent 7 years

(Cl. D58—12)

To all whom it may concern:

Be it known that we, Rollin H. Killoran and Charles F. Cruze, citizens of the United States, residing in the city of Los Angeles, county of Los Angeles, and State of California, have invented a new, original, and ornamental Design for a Box, of which the following is a specification, reference being had to the accompanying drawing, forming a part thereof.

Fig. 1 is a plan view of a box showing our new design; Fig. 2 is a side elevation of the box, and Fig. 3 is an end elevation of the box.

We claim:

The ornamental design for a box, as shown.

CHARLES F. CRUZE.
ROLLIN H. KILLORAN.
